Primary Examiner — John R Yeh*Assistant Examiner* — Dustin Andrew Griffith(74) Attorney, Agent, or Firm — Eversheds Sutherland (US) LLP(57) CLAIM

The ornamental design for a holster clip guard, as shown and described.

DESCRIPTION

FIG. 1 is a front view of a holster clip guard according to an embodiment of the disclosure;

FIG. 2 is a perspective view thereof;

FIG. 3 is a perspective view thereof;

FIG. 4 is a right view thereof;

FIG. 5 is a left view thereof; and,

FIG. 6 is a perspective view thereof.

The broken lines in FIGS. 1-6 depict portions of the holster clip guard that form no part of the claimed design.
